CHRISTMAS LIGHT REFLECTOR

Wayne B. Callahan, 16416 S. Bradfield,
Compton, Calif. 90221

Filed May 25, 1966, Ser. No. 2,435

Term of patent 14 years

(Cl. D48—16)

FIG. 1.

FIG. 2.

FIG. 3.

FIGURE 1 is a perspective view of a Christmas light reflector showing my new design.

FIGURE 2 is a plan view of the ornamental design of FIGURE 1.

FIGURE 3 is a side view of the ornamental design of FIGURE 2.

The broken line showing of a lamp bulb and socket structure is for illustrative purposes only.

What is claimed is:

The ornamental design for a Christmas light reflector, substantially as shown and described.
